George W. Emmert, Winnetka, Ill., assignor, by mesne assignments, to Federal Tool Corporation, Chicago, Ill., a corporation of Illinois

Application June 4, 1954, Serial No. 30,803

Term of patent 14 years

(Cl. D74—1)

To all whom it may concern:

Be it known that I, George W. Emmert, a citizen of the United States, residing at Winnetka, in the county of Cook and State of Illinois, have invented a new, original, and ornamental Design for a Tape Dispenser, of which the following is a specification, reference being had to the accompanying drawing forming a part hereof, in which:

Fig. 1 is a perspective view of a tape dispenser showing my new design;

Fig. 2 is a side elevational view of the tape dispenser shown in Fig. 1 as it appears with the cover in closed position;

Fig. 3 is a top plan view thereof;

Fig. 4 is an end elevational view as seen from the left of Fig. 2;

Fig. 5 is an end elevational view as seen from the right of Fig. 2;

Fig. 6 is a cross-sectional view thereof taken on line 6-6 of Fig. 5; and

Fig. 7 is a cross-sectional view taken on line 7-7 of Fig. 6.

The dotted line illustration in Figs. 1, 6 and 7 of a roll of tape, is for illustrative purposes only.

I claim:

The ornamental design for a tape dispenser, substantially as shown and described.
